FAST ROTATING WELL DRILL

Filed March 9, 1931

UNITED STATES PATENT OFFICE

FLOYD L. SCOTT AND LEWIS E. GARFIELD, OF HOUSTON, TEXAS, ASSIGNEES TO HUGHES
TOOL COMPANY, OF HOUSTON, TEXAS, A CORPORATION OF TEXAS

FAST ROTATING WELL DRILL

Application filed March 9, 1931. Serial No. 521,053.

Our invention relates to well drills of the rotary type for use in drilling deep wells for oil, water, gas and the like.

It is an object of the invention to provide a well drill arranged to be driven at a high rate of speed so that the drill may make good progress even where only a light weight is allowed to bear thereon.

We desire to obtain a straight hole without material deviation from the vertical by employing a rapidly rotating drill operating under light pressure.

Another object is to provide a tubular drill pipe connected with the drill for rotation, and a separate drive-shaft adapted to rotate the drill independently of the drill stem.

We aim to connect the sections of the drill stem and of the drive-shaft together at the joints by means easily coupled together and uncoupled when the drill stem is being introduced into or withdrawn from the hole.

The invention also includes means whereby the drill may be rotated directly by the drill stem in the usual manner, the drive-shaft remaining inoperative.

The invention also includes various points of novel construction residing in the details and arrangement of the parts making up our complete device.

In the drawings herewith Fig. 1 is a side view partly in elevation and partly in central longitudinal section showing the upper portion of the apparatus.

Fig. 2 is a similar view of the lower end of the structure. Figs. 3, 4 and 5 are transverse sections taken on the planes 3-3, 4-4 of Fig. 1 and 5-5 of Fig. 2 respectively.

The drill stem which we contemplate using includes tubular sections of drill pipe 1, which are generally similar to ordinary drill stem. The upper section may be connected to a head 2 of larger diameter to which may be connected a bail 3 by means of which the same may be connected with the traveling block 4 and cable ordinarily employed to suspend the drilling string in the derrick. Above the head 2, the diameter of the pipe is reduced and a swaged nipple 4 connects the stem with a member 5 connected to a fluid inlet pipe 6 similar to the usual goose-neck through which

flushing fluid may be pumped to the well.

The sections of drill stem are connected together by special tool joints including a pin member 7 and a box member 8. The pin member 7 has a threaded seat 9 into which may be engaged a spider 10 supporting a bearing bushing 11 for the drive-stem 12 which will be later described. The box-member 8 has a similar bearing support 13 screwed within a seat 14 in the joint.

The lower end of the drill pipe 1 is connected at 15 to the drill collar 16, the lower portion of which is formed with comparatively thick walls, the interior being beveled downwardly and inwardly at 17 to provide a seat 18 for a packing ring 19.

A mandrel 19 fits within the lower end of the drill stem. The lower position of this mandrel is reduced in diameter to extend through the lower end 16 of the drill collar, and is threaded at 20 to engage the head of the drill bit 21. The upper end of the mandrel has a squared recess 22 formed therein to receive the driving spindle 23 on the lower end of the drive-shaft 12. A ring 25 or cap 25, is fitted over the upper end of the mandrel within the drill pipe, thus leaving a small chamber 26 below the head 27 on the drive stem from which the flushing fluid may pass to the three ducts 28 leading downwardly to an axial channel 29 in the mandrel and the drill. A passage 30 in the head 27 of the drive stem conducts liquid to the chamber 26.

In the sides of the mandrel within the drill pipe are formed a plurality of recesses 31 to receive the clutch rollers 32. Said recesses are deep enough at one end to entirely receive the rollers, but the recesses taper toward one side to allow the roller to move into driving contact with the drill pipe. Thus, the pipe may drive the mandrel and the drill when the drill stem is moved in a clockwise direction, as seen in Fig. 5, but the relative rotation of the mandrel in that direction will not affect the drill pipe.

The drive-stem is a heavy shaft adapted to be rotated in the drill pipe by some source of power applied at the upper end 33 thereof which projects through the upper end of the

fluid chamber 5, with which it has a fluid tight fit. We have shown an electric motor 34 on said shaft, said motor being held stationary by means of an anchor rod 35 connected therewith. Said drive-shaft is made in sections of the same length as the drill pipe sections including the tool joints. Each section of drive-stem has a flange 36 thereon adjacent the upper end to rest upon one of the bearings 11 in the tool joint. Above the support the shaft has a squared end 37 to engage within a recess in one end of a coupling 38. Said coupling is long enough to receive the squared lower end of the next upper adjacent section of stem. Each coupling has a plurality of radial arms 39 which, if the coupling is dropped downwardly will engage the tapered portion 40 of the tool joint, and thus be prevented from further downward movement.

In the operation of the device, the drill stem may be rotated by the usual type of rotary table now in common use and not shown for purposes of clearness. This rotation of the drill stem in the usual right hand direction will rotate the drill bit, as described. When the bit is to be rotated at a rapid rate, the drive-stem is operated to rotate the drill, and it will be seen that this may be done independently of the drill pipe. That is, the drill pipe may rotate slowly, as is sometimes necessary to prevent sticking of the pipe, and at the same time the drive-stem may be rotated at a comparatively high speed to secure a rapid cutting action of the drill bit when a light load is rested on the drill. It is to be noted that a small longitudinal movement of the mandrel in the drill pipe is allowed, the drill collar 16 being movable along the mandrel 19 for a distance shown by the space 41 in Fig. 2.

What we claim as new is:

1. In a well drilling apparatus, a drill pipe, a drill bit at the lower end thereof, a connection between said drill pipe and said bit allowing relative rotation in one direction, a drive-shaft axially of said pipe connected with said bit, and means at the upper end of said pipe operatively connected with said shaft to rotate said bit independently of said drill pipe.

2. In a well drilling apparatus, a drill pipe, a drill bit at the lower end thereof, a one-way connection of said drill pipe to said drill bit, a drive-shaft detachably connected with said drill bit, and means at the upper end of said drill pipe to rotate said shaft and said bit independently of said pipe.

3. In a well drilling apparatus, a drill pipe, a drill bit thereon, an axial drive-shaft in said pipe connected with the upper end of said bit, said shaft projecting from the upper end of said pipe, and means connected with said shaft above said pipe to rotate said shaft

and said bit at a speed of rotation greater than that of the pipe.

4. In a well drilling apparatus, a drill pipe, a drill bit thereon, an axial drive-shaft in said pipe connected with the upper end of said bit, said shaft projecting from the upper end of said pipe, and means connected with said shaft above said pipe to rotate said shaft and said bit at a speed of rotation greater than that of the pipe, and means connecting said bit to said drill pipe for rotation of said bit when said drill pipe is rotated in one direction only.

5. A drill pipe, a bit thereon, a drive-shaft axially of said pipe, bearings in said pipe for said shaft, a motor at the upper end of said shaft, said shaft being detachably connected with said bit whereby said bit may be rotated independently of said pipe.

6. A sectional drill pipe, a drill bit at the lower end thereof, a sectional drive-shaft journaled axially of said drill pipe, joints in said shaft adjacent the ends of said drill pipe sections, means to support the sections of said shaft, and a driving connection between said shaft and said drill bit.

7. In a well drilling apparatus, a sectional drill pipe, a drill bit at the lower end thereof and having a driving connection therewith and means to drive said drill bit at a relatively fast speed including a drive-shaft in said drill pipe, connected with said bit, and a motor above said drill pipe and operatively connected with said shaft.

8. A sectional drill pipe, a drill bit thereon, a sectional drive-shaft journaled axially of said drill pipe, supports for the drive-shaft sections in the drill pipe sections, slideable couplings for said shaft in said pipe sections, adapted to be telescopically connected, and driving connections between said drive-shaft and said bit and between said drill pipe and said bit.

In testimony whereof, we hereunto affix our signatures, this the 27th day of February, 1931.

FLOYD L. SCOTT,
L. E. GARFIELD.
